(57) **CLAIM**

The ornamental design for a rear fender for an automobile, as
shown and described.

DESCRIPTION

FIG. 1 is a perspective view of a rear fender for an automobile
showing our new design;

FIG. 2 is a front view thereof;

FIG. 3 is rear view thereof;

FIG. 4 is a left side view thereof;

FIG. 5 is a right side view thereof;

FIG. 6 is a top plan view thereof; and,

FIG. 7 is a bottom view.

Our design includes the mirror image of the embodiment
depicted.
